METHOD OF AND APPARATUS FOR
IGNITING FUEL

William D. Hall, Elkins, W. Va.

Application March 29, 1946, Serial No. 658,195

13 Claims. (Cl. 175—115)

(Granted under the act of March 3, 1883, as
amended April 30, 1928; 370 O. G. 757)**1**

The invention described herein may be manufactured and used by or for the Government for governmental purposes, without the payment to me of any royalty thereon.

This invention relates to methods of and apparatus for igniting and burning combustible fuel and has several objects and advantages. The primary object is to provide starting methods and means which increases the probability of ignition and reduces the likelihood of explosions. Another object is to provide a switch which quickly cuts off the electrical igniter when combustion is established. Still other objects and advantages of my invention will appear as this description proceeds.

When the fuel valve of an electrically ignited burner is opened, the initial on-rush of combustible gases may so cool the igniter that combustion will not be effected. According to the invention now to be described, the supply of fuel is purposely decreased to a low steady quantity and then again increased to normal should it fail to ignite on the first effort at ignition. When this is done, the cooling effect on the igniter ceases for a short while and as the fuel again increases it will ordinarily ignite immediately. A further advantage of this method is that should ignition be attempted when the main control valve is wide open and admitting a very large quantity of gas, the supply of such gas is reduced during the ignition period. A still further advantage of this idea resides in the fact that in event ignition actually takes place the instant prior to reduction in the quantity of fuel that the flame will not be extinguished but will continue to burn.

It is common in the art to deenergize an electrical igniter with a series connected thermostatic switch. Such a switch does not instantly deenergize the igniter when combustion is established. During the interval when both the flame and the current are heating the igniter the latter deteriorates. For this reason it is desirable to reduce the time lag of response of the thermostatic switch as much as possible in order that it may open the circuit and deenergize the igniter as soon as combustion takes place. I have reduced this time lag of response by making the igniter current as well as the specific resistivity of the thermal element of the switch large so that the thermal element is appreciably heated by the igniter current before the switch breaks its circuit. The thermal element therefore rises to a temperature where it will break its circuit rapidly because it receives heat generated direct-

2

ly inside of the same prior to establishment of combustion and is already heated to some degree before the flame heats it. This will be discussed in detail later.

5 I have illustrated the various parts of my invention rather diagrammatically in the accompanying drawings since my invention relates to methods and systems generally rather than to specific details of design of a particular system. 10 Figure 1 illustrates fuel burning apparatus on which my invention may be performed manually. Figure 2 illustrates schematically certain apparatus that will automatically operate in accordance with the principles of my invention. 15 Figure 3 illustrates schematically another form of the invention. Figures 1 and 2 of this application and the description applicable thereto are identical with corresponding figures and description in my now abandoned prior copending 20 application S. N. 379,586, filed February 19, 1941, entitled the same as the present case and of which the present case is a continuation-in-part.

In Figure 1 a source of electricity which may be a six volt storage battery supplies power to 25 wires 10 and 11. A switch 12 is used to close the circuit and initiate operation of the system. A bimetallic strip 13 is supported in the vicinity of the burner 19 by the bracket 14. Strip 13 carries a contact point 15 which normally engages contact point 16, that is, it engages point 16 when the burner is cool. When the strip 13 is heated, it moves contact point 15 to the right and breaks contact between that point and its complementary contact point 16. Contact point 16 is carried by a stationary support 17 and connects electrically to one end of the electrical resistance igniter coil 18, which coil may be directly above the burner 19 and in the path of the oncoming fuel. While the igniter coil 18 is shown in direct 30 operative relation with the burner 19 I wish to state that such coil may be operatively associated with the burner in any of the well known indirect methods known to the art. The gas issuing from the burner 19 is ignited by the coil 18, 35 and such gas is fed to the burner through the fuel feed line 20. A valve 21 is located in pipe 20 but this valve is so constructed that it never completely closes the fuel feed line. Even when the valve 21 is fully seated, a space 22 is open which permits some fuel to flow to the burner. A handle 23 is controlled manually and it in turn 40 controls the valve 21. The valve 21 has enough friction in its operation that it will remain fully open or fully seated as the case may be when it 45 is left in either of these positions. A main con-

trol valve V may be used to completely shut down the system or to regulate the quantity of fuel fed thereto.

To carry out the invention manually with the system of Figure 1, the switch 12 is first closed. When this is done, the igniter coil 18 is immediately energized and at the same time current flows through the bimetallic strip 13 heating it. Valves V and 21 are then completely opened in turn to the desired degree. If valve 21 is already completely open as would ordinarily be the case, only valve V need be opened. When these valves are opened the supply of fuel may increase either gradually or very rapidly depending on how fast they are opened. In either event the fuel may fail to ignite in which event the valve 21 should be fully seated for a few seconds or so and then again fully opened. It is very probable that should the fuel fail to ignite on the first effort due to improper combustion conditions that it will ignite this second time. If the fuel ignited at precisely the instant that the supply of fuel was decreased, the flame will not extinguish because valve 21 does not fully close. As has been stated there is an opening 22 below the valve 21 which permits some fuel to flow to the burner even when the valve is fully seated. Should the fuel fail to be ignited on the first or the second efforts, the valve handle 23 may be repeatedly operated up and down until the fuel does ignite. It may be operated up and down either fast or slow depending on which manner is found most effective under particular circumstances. During all this time, the igniter coil 18 remains continuously energized.

As soon as the fuel ignites, the strip 13 is heated and tends to open the circuit at contacts 15 and 16. The prior art shows the same electrical circuit as I have shown in Figure 1, however, I contemplate a bimetallic strip 13 of such size and resistivity that it will be appreciably heated by the flow of current therethrough to the igniter. Therefore, prior to the time the thermostatic switch 13, 15 breaks the igniter circuit the bimetallic strip 13 is heated by the current and due to this heating breaks the circuit in less time than it otherwise would. This feature also permits the design to operate the switch 13 at a higher temperature without increasing the response time above that now used; hence the switch 13 recloses the circuit quickly when the flame becomes extinguished. By generating the pre-heating directly inside of the bimetallic strip 13 the effect of the heating is much more rapid than it is when such pre-heating is accomplished by a series resistor near the strip. The degree to which bimetallic strip 13 is heated by the igniter current therethrough may be (a) sufficient to actually break the circuit at contacts 15, 16 even if the fuel completely fails to ignite at any time, or (b) it may be insufficient to actually break the circuit at 15, 16 until additional heat is supplied by the flame. Preferably the heating is sufficient to bring the temperature of the strip 13 almost up to the point at which it breaks the circuit at contacts 15, 16. In this case only a slight additional heating is necessary from the flame to break the circuit and deenergize the igniter and of course this small amount of heat will be supplied almost instantly after the fuel is ignited. Of course, my claims are not to be limited to this high degree of perfection but broadly cover the case where appreciable heat is generated inside strip 13.

The apparatus of Figure 2 will automatically accomplish the functions performed manually on

the device of Figure 1. The various parts of Figure 2 that bear reference numbers common to Figure 1 are identical in construction and operation to similar parts of Figure 1.

In Figure 2, the valve 21 is operated by a cam follower 26. The follower or roller 26 is held in contact with the cam 29 by a spring 24. The spring 24 is based upon pipe 20 and presses upward on arm 25 which arm is rigidly fastened to the valve 21. The cam 29 is pivoted off center at 28 and is driven by a motor 32. Contact points 30 and 31 are separated when the valve 21 is open and the contacts are together when the valve 21 is fully seated. The parts are shown in the normal "off" position just prior to turning it to the "on" position. To start the apparatus, the switch 12 is thrown "on" thus establishing an igniter circuit as follows: 10—12—14—13—15—16—17—18—11. The igniter 18 begins to become hot and strip 13 is preheated due to the large igniter current flowing therethrough. The motor 32 is also energized by the following path: 10—12—13—15—16—17—33—32—11. Resistor 33 is not large enough to prevent energization of the motor by this circuit. If the fuel ignites immediately, the switch 13 will break the igniter circuit as well as the motor circuit quickly, thereby leaving valve 21 fully open. If on the other hand the fuel should fail to ignite on the first effort, motor 32 will begin to rotate the cam 29 slowly (as the motor is provided with suitable mechanism whereby it rotates the cam only very slowly). It requires say twenty seconds or so to revolve the cam 29 a half revolution. When the valve 21 approaches a seated position, contacts 30 and 31 engage each other and thereby energize the motor as follows: 10—12—14—13—flexible lead 27—25—30—31—19—32—11. The motor is now energized independently of switch 15, 16 and will remain running until the valve 21 is unseated. If by that time the fuel has ignited and has broken the circuit at contacts 15, 16 the motor will stop in a valve-open position upon the breaking of contacts 30 and 31. It is noted that the motor can never stop in a valve-closed position. If the fuel fails to ignite, the cam 29 will continue to rotate thereby intermittently opening and seating the valve 21 and will therefore repeatedly decrease and increase the flow of gas striking the igniter coil 18 which of course remains energized continuously. If switch 13 opens while the valve is seated, the igniter 18 will drop in temperature slightly below incandescence due to resistor 33 but will still be heated by the circuit 10—12—14—13—27—25—30—31—33—18—11, until finally the valve 21 is fully unseated at which time the igniter is completely deenergized due to the separation of contacts 30 and 31.

If the self-heating of switch 13 is designed to be sufficient to actually break the circuit by reason of the heavy igniter current therethrough even in event the flame never is established; then the igniter 18 will be intermittently increased and decreased in energization. Similarly the valve 21 will repeatedly open and reseat itself.

If the flame ignites, continues to burn for a while, then becomes extinguished, switch 15, 16 will close and cause the motor 32 to rotate cam 29 just as in the case of an initial ignition attempt. This will automatically attempt to make several new attempts to again establish combustion.

In Figure 3, a hot wire igniter 18 is connected to the center tap 50 of the secondary of current transformer 51. The ends 52 and 53 of

the secondary winding connect to the U-shaped bimetallic member 54 which normally maintains contact with contact point 55 but bends upward and away from 55 when member 54 is heated. Contact 55 is in series with primary winding 56 and with source 57, 58. The motor 32 across the igniter operates the cam 28, cam follower 26, and valve 21 as is more completely shown in detail in Figure 2.

In Figure 3, when the starting switch is closed, current flows as follows: 58—18—50—52—53—54—55—56—12—57. Flow of current through primary winding 56 causes a heavy current to flow in the secondary which current circulates through the U-shaped member 54. This heating causes member 54 to be thoroughly heated and to greatly aid the heat of combustion in heating member 54 so as to break the circuit at 55. After contact at 55 is broken the member 54 is heated by the flame only. The principles of operation of Figure 3 can readily be understood from the above description especially in view of the more detailed explanations of Figures 1 and 2.

I claim to have invented:

1. A heating system comprising in combination, a fuel burner; a hot-wire igniter therefor; a fuel feed line to said burner; electrical means having two terminals by which the same may be energized and which when energized intermittently increases and decreases the quantity of fuel fed through said feed line; a thermal switch comprising a bimetallic strip and contacts associated with, and separated by, the strip when the strip is heated, and closed by the strip when the strip is cooled; one of said contacts being electrically connected to one end of said strip; a wire electrically connecting the other of said contacts to one of said terminals and also to one side of said hot-wire igniter; a wire adapted for connection to a source of electrical supply and connecting the remaining terminal as well as the remaining end of said hot-wire igniter to one side of such source; another wire also adapted for connection to a source of electrical supply for connecting the remaining end of said bimetallic strip in such a manner that current from said source flows directly throughout the length of said bimetallic strip before reaching said contacts; and means supporting said bimetallic strip to position the same responsive to the heat of combustion; said strip comprising materials of such size and resistivity that the flow of current directly therethrough to said igniter will generate appreciable heat directly inside the strip and raise the temperature of the strip close to the actual temperature required by the strip in order to separate said contacts, whereby the strip will operate to quickly separate the contacts in response to combustion of fuel at said fuel burner.

2. In a fuel burning system, a burner, a hot-wire igniter therefor, a thermal switch comprising a thermal element, said thermal switch being connected directly in series with said igniter and such that the current to the igniter flows directly through said thermal element, means supporting said thermal element responsive to combustion at said burner, and means operable to feed fuel to said burner; said thermal element and said igniter being composed of materials of such size and resistivity that when energized the heating generated directly inside of said thermal element by the igniter current fed therethrough will appreciably raise the temperature of said element.

3. The system of claim 2 wherein the resistivity of said element is so high that the heat gen-

erated directly in the thermal element is so great as to cause the switch to deenergize the igniter even in absence of heat of combustion.

4. The system of claim 2 in which the resistivity of the thermal element is sufficiently low that the heating thereof due to the current flowing therethrough will raise the temperature thereof above ambient to a lower value than is required to break the igniter circuit.

5. In a heating system, a space wherein fuel is burned, electrical energized ignition means adapted to ignite the fuel when such means is energized, a circuit for energizing said ignition means and including a control means in series with the circuit, said control means including a thermal element for operating the same to break the circuit when said element is heated and to close the circuit when said element is cooled, said control means comprising means for effecting flow of sufficient current directly through said element when and only when the igniter is energized to appreciably heat said element and provide at least ten percent of the amount of heating that is required to be supplied to said element in order for the circuit to be broken by said element, whereby to reduce the time lag of response thereof to combustion, and supporting means positioning the thermal element responsive to the heat of combustion.

6. The method of utilizing an igniter of the hot-member type to establish combustion of fuel at a burner which includes heating the igniter, establishing a flow of fuel operatively near the igniter, and maintaining the igniter continuously energized while the supply of fuel is decreased to a low but substantial value at which it will sustain combustion if a flame was established on the first effort and subsequently increased.

7. The method of utilizing an igniter of the hot-member type to establish combustion at a burner which includes varying the fuel flow rate across the igniter between a high rate and a low substantial rate while maintaining the igniter continuously energized.

8. In a heating system, a burner, a hot-member type igniter therefor, fuel feeding means, means for energizing the igniter and maintaining the same continuously energized until combustion is established, and means for making more than one effort to effect combustion of the fuel at the burner, the last-named means comprising means for initially increasing the flow of fuel so as to make a first effort and in event that effort fails to reduce such flow to a lower but appreciable quantity and subsequently again increase such flow.

9. The method of utilizing an igniter of the hot-member type to establish combustion of fuel at a burner which includes heating the igniter, establishing a flow of fuel operatively near the igniter so as to cool the igniter if ignition is not effected, reducing the quantity of fuel fed near the igniter so that the igniter can rise in temperature yet maintaining at all times sufficient flow of fuel that if combustion is established that it will sustain itself, and subsequently again increasing the flow of fuel.

10. In a heating system; a burner, a hot wire igniter that consumes a large current when operating; said igniter being positioned near the burner so as to ignite fuel thereat; a thermal element composed of a high resistivity bimetallic strip; a stationary supporting current connection at one end of said bimetallic strip; a contact point carried by the other end of said bimetallic

strip; a stationary current connection having a complementary contact point for the first-named contact point; wires energized by a low voltage large current supply for forcing the large current through said strip and igniter; said wires forming a series circuit from the source to and through the igniter, to one of said stationary current connections, through said strip to the other stationary current connection, and back to the source; said bimetallic strip being positioned in the region of heat from the burner and operable upon establishment of combustion to rise in temperature and move said contacts to a separated position to thereby break the igniter circuit and deenergize the hot wire igniter in a predetermined time interval after combustion is established, and said bimetallic strip comprising means whereby the large igniter current flowing therethrough generates sufficient heat directly inside of said bimetallic strip as to materially and substantially reduce the time required to break the igniter circuit below the time that would be required in event there was no heat generated in the bimetallic strip by the igniter current; and switching means operable to control the igniter circuit to close the same, activate the igniter, and effectuate the said heating in said bimetallic strip.

11. The heating system defined by claim 5 in which the igniter is a hot-wire type igniter, and in which the thermal element consists of high resistivity material.

12. The device defined by claim 5 in which said control means comprises a current transformer having its primary in series with said circuit and its secondary connected across at least a portion of said element so as to pass a heavy current through the latter.

13. In a burner control system, a hot-wire igniter, a circuit energizing the igniter, a transformer having a primary winding in series with said circuit, said transformer having a secondary winding, and thermostatic means comprising a bimetallic strip a portion of which is shunted across said secondary winding and thereby is heated by current from said secondary winding, means supporting said thermostatic means near the flame so as to be heated thereby, and a switch in series with said circuit and operated by said thermostatic means to break said circuit when said thermostatic means is hot and to close said circuit when said thermostatic means is cool; 10
14. said bimetallic strip and said igniter circuit being of such impedances that when energized the heating in said bimetallic strip by the current passing therethrough will appreciably raise the temperature of said bimetallic strip and thereby 15
16. cause the igniter to be deenergized more promptly than it would have been deenergized had the bimetallic strip been heated solely by heat from the flame.

WILLIAM D. HALL.
